CLAIM

The ornamental design for a shoe sole, as shown and described.

DESCRIPTION

FIG. 1 is a top left front perspective view of the shoe sole showing a first embodiment of my new design;

FIG. 2 is a top left rear perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof; and,

FIG. 8 is a bottom view thereof.

The broken lines in the figures illustrate portions of a shoe which are environmental to the shoe sole and form no part of the claimed design.

1 Claim, 7 Drawing Sheets(56)
